UNITED STATES PATENT OFFICE.

FRANK E. RICHARDSON, OF JACKSON, ALABAMA.

VENTILATING-PANEL.

No. 894,536.

Specification of Letters Patent.

Patented July 28, 1908.

Application filed November 11, 1907. Serial No. 401,727.

To all whom it may concern:

Be it known that I, FRANK E. RICHARDSON, a citizen of the United States, residing at Jackson, in the county of Clark and State 5 of Alabama, have invented certain new and useful Improvements in Ventilating-Panels, of which the following is a specification, reference being had therein to the accompanying drawing.

10 This invention relates to panels intended for insertion in doors, windows, or walls of cars and the like, for the purpose of admitting air while excluding cinders and dust. For illustration, the devices are shown in a 15 door, but they may be used in any situation where it is desired to admit air, or air and light.

In the accompanying drawings, Figure 1 is an end elevation of a car body having its 20 door provided with my devices. Fig. 2 is a section on the line 2—2, Fig. 1. Fig. 3 is a section on the line 3—3, Fig. 1.

In these views, A represents a door having in its upper part or ordinary panel space three 25 parallel, perforated plates, B, C, D, the perforations of each plate preferably being of a different size from those of the other plates. The middle plate is stationary in the door while the others are secured in frames E re- 30 spectively, hinged at F to the body of the door to swing outward. These two plates are each at some distance from the middle plate, and for convenience they are provided with knobs G and are secured in closed position by suitable fastenings H. Within the 35 body of the door, below these plates, is a cavity I opening laterally near its bottom by means of a narrow door J to allow the insertion and removal of a dust trough K. A 40 fourth plate L without perforations is arranged to slide vertically, between the planes of two of the three plates, in ways M. Ordinarily this plate rests in the recess below the other plates, as shown, but if it be desired to 45 prevent or restrict the entrance of air, it may be wholly or partially raised and secured by any suitable catch at N. The perforations in adjacent plates are out of registry so that air passing through must take a devious 50 course.

The devices being thus arranged, air escaping from the car or other chamber, either naturally or through the action of special devices, will be replaced by air entering 55 through the plates. The air on passing through the outer plate is sharply deflected

in passing to the apertures in the next plate, and cinders and dust particles, which are materially heavier than the air, will drop out of the most rapidly moving part of the air, 60 which passes through the next succeeding apertures, and falling below the plates will come to rest in the dust trough. This action being repeated, by reason of having three plates, practically little dust and no 65 cinders enter the car. The holes in the different plates being of different sizes, the velocity of the air is varied, and this apparently assists in eliminating dust.

The operation described is not affected by 70 the presence or absence of the imperforate plate, and the latter may be omitted when it is not desired to provide for controlling the admission of air by cutting off in whole or in part the passages through which it enters. 75

Preferably all the plates are made of glass, since light is usually desirable and rarely detrimental, yet where light is not essential expense may be saved by employing other material. When glass is used, it should be 80 "wire glass", as indicated in the plate D, the perforations being made to pass through the meshes of the wire.

What I claim is:

1. A ventilating light transmitting panel 85 consisting of a perforated glass plate fixed in a suitable frame and two auxiliary perforated glass plates upon opposite sides of the fixed plate, parallel thereto, at some distance therefrom, and arranged for ready removal 90 to permit access to all the glass surfaces.

2. A ventilating apparatus comprising a series of registering parallel glass plates spaced apart and provided with non-registering perforations, hinged frames normally 95 holding the outer plates in parallel relation and an imperforate glass plate arranged to slide, between the perforated plates, into and out of registry with the latter.

3. A ventilating apparatus comprising a 100 suitable frame, a series of parallel registering perforated plates spaced apart in the upper part of said frame, a dust receptacle, below said plates, in position to receive all matter falling from between them, said frame being provided with a normally closed opening for removing said receptacle.

4. A door having in its upper part a series of parallel registering glass plates spaced apart and provided with non-registering perforations, and further having below the plates a 110 passage communicating with the exterior of

the door and connected, with the space between the plates, for the escape of dust falling between the plates.

5. The combination with a door having an upper panel space and an internal cavity below said space, of a small door for opening said cavity, of a dust receptacle in said cavity adjacent to said small door, a panel occupying said panel space and consisting of a 10 central perforated glass plate secured in the door, parallel perforated glass plates hinged upon opposite sides of the plate first men-

tioned and having their perforations out of registry with those of the first plate, and an imperforate glass plate normally lying in said cavity and arranged for sliding upward into the panel space to control the passage of air. 15

In testimony whereof I affix my signature in presence of two witnesses.

FRANK E. RICHARDSON.
